UNITED STATES PATENT OFFICE.

JOHN N. BUSELL, OF BOSTON, MASSACHUSETTS, ASSIGNOR TO UNITED SHOE MACHINERY COMPANY, OF PATERSON, NEW JERSEY, A CORPORATION OF NEW JERSEY.

DUST-HOOD.

1,034,073.

Specification of Letters Patent. Patented July 30, 1912.

Application filed April 1, 1912. Serial No. 687,820.

To all whom it may concern:

Be it known that I, JOHN N. BUSELL, a citizen of the United States, residing at Boston, in the county of Suffolk and State of Massachusetts, have invented certain Improvements in Dust-Hoods, of which the following description, in connection with the accompanying drawings, is a specification, like reference characters on the drawings indicating like parts in the several figures.

This invention relates to dust hoods designed to be used on machines for abrading, scouring or trimming portions of boots or shoes, such as the heel or sole edges.

In machines of this general character the tools necessarily are driven at a very high speed and their action upon the work produces a great quantity of dust and chips which, if not carried away in some manner, subject the workman to great annoyance and, by working into the bearings and running parts of the machine, seriously impair its running qualities. In order to avoid this condition many forms of dust hoods have been devised and connected with some form of an exhaust apparatus to catch the dust and shavings thrown from the tools and conduct them away from the machine. Such hoods, however, have usually been so constructed heretofore that they have interfered with the proper manipulation of the shoe during the operation of the tool thereon.

It is the purpose of this invention to provide a dust hood which, while serving effectually to catch and conduct away from the machine the dust produced by the tools, shall also be free from the objection just noted. The particular manner in which this object is effected will be clearly understood from the following description of one embodiment of the invention, reference being made to the accompanying drawing, in which—

Figure 1 is a view in front elevation of a machine equipped with a hood constructed in accordance with this invention; and Fig. 2 is a plan view of the board and part of the machine shown in Fig. 1.

The drawings show a commercial form of machine for trimming the edges of the soles of shoes. This machine comprises a frame 2 supporting an upper shaft 4, upon which is mounted a cutter 6 shaped to trim the forepart of the sole. Another shaft 8, also supported in the frame 2, carries a cutter 10

shaped to trim the shank portions of the sole edge, this cutter being positioned below and at one side of the forepart cutter 6.

The dust hood shown in the drawings comprises a dust trunk 12 having a horizontal portion and a depending portion 14 designed to be connected with any suitable exhaust system. A main branch 16 extends forwardly from the horizontal portion of the trunk 12 to a point close to the forepart cutter 6. This branch is substantially rectangular in cross section but decreases in cross sectional area toward its forward end. It will be understood by those skilled in this art that the shoe is usually presented to the lower side of the cutter so that, while the hood may project somewhat over the top of the cutter, it must be cut away below the cutter sufficiently to afford ample space in which to handle the shoe. The cutters rotate in a clockwise direction and thus throw the chips and dust backwardly toward the trunk 12. Accordingly, the dust receiving mouth of the branch 16 is extended downwardly and backwardly from a point adjacent to the cutter 6 and is flared to enable it to catch substantially all of the dust as that is thrown from the cutter 6. The rear wall 18 of the mouth is substantially vertical and extends for a considerable distance below the level of the cutter where it acts as an apron to catch the dust enabling the draft of air through the mouth to carry it into the branch 16. Another branch 20 communicates with the trunk 12 and extends forward from a point beside the branch 16, diagonally away from the branch 16 and downward to a point substantially opposite the position that the heel of the shoe normally will occupy when the workman is trimming the forepart close to its junction with the shank on the left hand side of the shoe. (See Fig. 2.) The branch 20 is curved outwardly or offset away from the branch 16 sufficiently to position it entirely outside the range of movement of the shoe during the trimming of the forepart. From this point the branch 20 extends inwardly or toward the branch 16 to a point close to the shank cutter 10, its dust receiving mouth being positioned adjacent to this cutter where it will catch the dust and chips thrown therefrom. Since the shank portions of the sole edge each lie in a concave curve, it will be evident then when the

workman is trimming these portions of the edge the part of the shoe that extends back of the cutter must be swung into a position higher than the level of the cutter itself. 5 The inclination laterally and upwardly away from the cutter of that part of the branch 20 immediately behind its mouth results in leading the branch away from the position normally occupied by the shoe 10 while it is being trimmed in a direction such that it can not interfere with the free manipulation of the shoe. The branches 16 and 20 are joined together at their adjacent ends and the trunk 12 is telescoped over them. The trunk may therefore be removed 15 and turned into a position the reverse of that in which it is shown, so that the part 14 can be connected with an exhaust system located above the machine. A shelf 22 connects the branches 16 and 20 and has a hole punched therethrough to receive the stem of an oil cup 24 by which the hood may be supported upon the machine frame 2. The 20 hood may be made of sheet metal or of any other suitable material. 25

Having thus described my invention, what I claim as new and desire to secure by Letters Patent of the United States is:—

1. In a sole edge trimming machine hav-

ing a forepart cutter and a shank cutter, the 30 shank cutter being positioned below and at one side of the forepart cutter, a dust trunk, a branch leading therefrom having a dust receiving mouth positioned adjacent to the forepart cutter, a second branch leading 35 from said trunk extending diagonally away from the first branch and downwardly to a point close to the shank cutter, said branch lying outside the range of movement of the shoe during the operation of the cutters 40 thereon.

2. A dust hood comprising a trunk, a branch communicating with said trunk and extending forwardly therefrom, said branch having a dust receiving mouth, and a second 45 branch also communicating with said trunk, having a dust receiving mouth positioned at one side of and below the mouth of the first branch, the part of said second branch immediately behind its mouth being offset lat- 50 erally away from the first branch.

In testimony whereof I have signed my name to this specification in the presence of two subscribing witnesses.

JOHN N. BUSELL.

HENRY KAHLMEYER.

Copies of this patent may be obtained for five cents each, by addressing the "Commissioner of Patents, Washington, D. C."

It is hereby certified that in Letters Patent No. 1,034,073, granted July 30, 1912, upon the application of John N. Busell, of Boston, Massachusetts, for an improvement in "Dust-Hoods," an error appears in the printed specification requiring correction as follows: Page 1, line 47, for the word "board" read *hood*; and that the said Letters Patent should be read with this correction therein that the same may conform to the record of the case in the Patent Office.

Signed and sealed this 22d day of October, A. D., 1912.

[SEAL.]

C. C. BILLINGS,

Acting Commissioner of Patents.
